UNITED STATES PATENT OFFICE.

JOHN GRIFFIN DURANT, JR., OF HUNTINGTON, WEST VIRGINIA.

RAIL TIE.

Application filed October 19, 1927. Serial No. 227,264.

My invention relates to rail ties of that type in which the tie and clamping members are secured together so that it is only necessary to place the rails on the tie and manipulate the clamping members to hold the rail securely in place, there being no parts detached or to be detached from, and replaced onto the tie when securing the rail in place. It is so constructed as to be slipped as a unit.

The object of the invention is to obtain a surer hold of the rail in place; to provide means secured to the tie movable into and out of engagement with the rail to hold the rail down to the tie, which means co-operate with other means integral with the tie to hold the first mentioned means, the whole structure being of ready operation and cheaply made.

Specifically, the tie engages the outer side of the rail and has lugs engaging the inner edge of the rail foot or flange with a movable latch secured to the tie that engages the upper face of the inner rail flange and is held in engagement with such flange by said lugs.

Referring to the drawings in which like parts are similarly designated:

Figure 1 is an elevation of one end of a railway tie in elevation with the rail thereon shown in cross-section.

Fig. 2 is a plan view of the tie with the latch removed.

Fig. 3 is a plan view of the latch.

The tie 5 is made of a rolled shape here shown as a simple channel. It has upturned ends 6 engaging the edge of the outer rail flange. Each upturned end follows along the upper face of the outer flange as at 7 and then has a vertical portion 8 parallel with and preferably lying against the web of the rail.

The opposite inner edge of the rail foot is engaged by two lugs 9 struck up from and integral with the tie.

These lugs have a hump 10 that gradually merges into the body of the tie, their free ends engaging the inner edge of the rail foot.

The lugs 9 have a certain resiliency and are spaced toward the inside of track a sufficient distance so that the foot of the rail will fit between them and the bent-up end 6, 7, 8 of the tie.

Between the lugs 9 is located a metal plate 11 latch shown in plan in Fig. 3, having a hole 12 for registering with a hole 13 in the tie

somewhat farther toward the inside of the track than lugs 9.

This latch has a flat bearing portion 13, an inclined rail foot engaging portion 14 terminating in an upturned portion 15 and a tail portion 16 preferably arched. The latch is held to the tie by a rivet 17 or equivalent.

The upturned nose 15 of the latch lies under the head of the rail and preferably is spaced from the rail web so as to be readily struck with a hammer.

The tail of the latch is for a similar purpose. The latch when in its engaging position lies between the two lugs 9 and they prevent the latch from being accidentally turned on its pivot 17, that is to say, the arrangement is such that the lugs perform the double purpose of holding the rail foot and also holding the latch in latching position.

The resiliency of the inclined portion 14 of the latch, the distance of the pivot 17 from the rail engaging end of the latch, the necessary looseness to effect pivotal action of the latch on rivet 17 and some slight resiliency in the lugs 9, will permit the latch to be knocked over the lugs either into latching position or unlatching position by a heavy hammer blow either on the upturned nose 15 or on the tail 16.

This is facilitated by the curvature of the lugs which provide camming surfaces *a* and *b*.

The free ends of the lugs do not lie above the under face of the inclined portion 14 of the latch so that when releasing the latch from the rail it will more readily slide up the portion *a* of the lug.

When closing the latch the portions *b* of the lugs act to cam up the latch when struck and facilitate its being knocked into latching position between the lugs.

I claim:

1. A rail tie having means for engaging the outer flange of a rail and lugs engaging the inner rail flange in combination with a latch pivoted to the tie and held in latching engagement with the rail by said lugs.

2. A rail tie having lugs for engaging the inner edge of the rail flange and a latch pivoted to the tie at a point farther from the rail than said lugs and held between the lugs in rail engaging position.

3. A rail tie having a pair of struck-up lugs having a hump and a rail foot engaging latch pivoted to the tie and arranged to

be forced over said humps into latching position between the lugs.

4. A rail tie having a pair of lugs for engaging the edge of a rail flange and having humps, a latch pivoted to the tie having a flat pivoting portion and an inclined rail foot engaging portion arranged to ride over said humps and to be held in operative position by the lugs.
5. The combination of a rail tie having upturned ends for embracing the outer side of a rail foot and extending along the rail web and a pair of humped lugs struck up from the tie whose face ends are arranged to engage the inner edge of the rail foot in combination with a latch pivoted to the tie between said lugs and held thereby and having

a nose spaced from the head and web of the rail.

6. The combination with a channel shaped rail tie having upturned ends for embracing the outer side of the rail foot and extending along the rail web and a pair of humped lugs struck up from the tie whose free ends are arranged to engage the inner edge of the rail foot; a latch pivoted to the tie back of said lugs and of a width substantially the distance apart of the lugs, arranged to engage the top of the rail foot and having upturned ends for being struck by a hammer.

In testimony that I claim the foregoing as my invention, I have signed my name:

JOHN GRIFFIN DURANT, JR.
